UNITED STATES PATENT OFFICE.

GEORGE CROMPTON, OF WORCESTER, MASSACHUSETTS.

IMPROVEMENT IN LOOM-PICKERS.

Specification forming part of Letters Patent No. 148,936, dated March 24, 1874; application filed March 4, 1874.

To all whom it may concern:

Be it known that I, GEORGE CROMPTON, of Worcester, in the county of Worcester and State of Massachusetts, have invented an Improvement in Loom-Pickers; and I do hereby declare that the following, taken in connection with the drawings which accompany and form part of this specification, is a description of my invention sufficient to enable those skilled in the art to practice it.

The invention relates to such a construction of the picker as shall render it more enduring under the blows or abrasive contact of the picker-staff.

In my invention I make the picker of raw-hide, bent, formed, and having its parts held in place in the usual manner, and adjacent to the tube through which the guide-rod runs I embrace the web or thin part of the picker between two straps or arms of a curved metal shoe or guard that covers the end of the picker, in the plane of movement of the picker-staff, said shoe extending beyond the picker vertically in opposite directions, or in the plane of the picker-staff, and the picker-staff, in acting against the pick, having to a great extent a rolling or rocking motion upon the face of the metal guard or shoe, instead of an abrasive or sliding motion only, as when it acts directly against the picker. The invention consists of a picker having such metal guard or shoe, against which the picker-staff directly acts.

The drawing represents a picker embodying my invention. Figure 1 shows the same in plan. Fig. 2 is an end view of it. Fig. 3 is

an opposite end view. Fig. 4 is a bottom view. Fig. 5 is a front view.

a denotes the picker, formed of layered rawhide, wound solid to make the part *b*, that strikes the shuttle, and with a straight thin or web part, *c*, that connects the part *b* with the tubular end *d*, through which runs the rod that the picker slides upon. Adjacent to the tube *d* is seen the metal guard or shoe *e*, said guard extending above and below and across the end of the picker, and being curved, as seen in Fig. 5. The guard has extending from its inner side two strap-plates, *f* *g*, that embrace the picker and hold the guard or shoe in position, the straps being fastened by pins or rivets passing through both and through the picker. Through an eye, *h*, and socket *i*, a cord or strap may pass to fasten the picker to the picker-staff.

The picker-staff, as before observed, acts against the metal guard, and not directly against the picker, and it will be obvious that by the intervention of this guard and the form of its face the picker and picker-staff will both be protected from injury by abrasive wear.

The picker-guard I prefer to form as a malleable-iron casting.

I claim—

The picker having the metal guard or shoe *e*, formed and applied substantially as described.

GEO. CROMPTON.
